UNITED STATES PATENT OFFICE

KALLE RINNE, OF TOWNSEND, MASSACHUSETTS

COMBINED HOLDER AND SNUFFER FOR CIGARETTES

Application filed August 28, 1930. Serial No. 478,519.

This invention relates to a combined holder and snuffer device designed primarily for use in connection with cigarettes, but it is to be understood that a device in accordance with this invention may be employed in any connection for which it may be found applicable, and the invention has for its object to provide, in a manner as hereinafter set forth, a device of the class referred to so constructed and arranged for expeditiously and detachably connecting therewith a cigarette in position to be smoked, permitting of the attached cigarette being conveniently positioned between and removed from the lips of the smoker when occasion requires, and further for automatically snuffing off the lighted end of a cigarette when the latter has been consumed to the point of attachment of the device with the cigarette.

20 Further objects of the invention are to provide, in a manner as hereinafter set forth, a combined cigarette holder and snuffer which is simple in its construction and arrangement, strong, durable, compact, thoroughly efficient in its use, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

30 In the drawings wherein like reference characters denote corresponding parts throughout the several views:

40 Figure 1 is a perspective view showing the adaptation of a combined holder and snuffer in accordance with this invention with respect to a cigarette.

Figure 2 is a side elevation of the device illustrating the same in connected position with respect to the cigarette and with the cigarette shown in dotted lines.

45 Figure 3 is a side elevation of the device in position after it has performed its snuffing function.

Figure 4 is a fragmentary view of the device in perspective illustrating the position thereof after it has performed its snuffing function.

The body portion of the device is formed 55 from a single length of spring wire of the desired gauge and includes a handle part, a pair of arms and a pair of oppositely disposed combined cigarette clamping and snuffer elements. The handle part, arms 60 and elements will be more specifically referred to.

The material from which the body portion is set up is bent to provide a handle part 1 in the form of a resilient, split loop which merges into a pair of resilient arms 2, 3 of the desired length. The arms 2, 3 are integral with the ends 4, 5, respectively of the handle part 1. The arm 2 is coiled intermediate its ends, as at 6.

70 The outer end of the arm 2 merges into a semi-circular part 7, the latter at one end terminates in a laterally disposed, rounded bend 8 which merges into a semi-circular part 9 formed at its free end with an angularly disposed portion 10 extending towards the part 7 and seating on the outer end of arm 2. The semi-circular parts 7, 9 are arranged in opposed, spaced relation and in connection with the parts 8, 10 provide a slot for a purpose to be referred to. The parts 7, 9 centrally thereof are coupled together by a cross-piece 11 and the latter functions in connection with the bend 8 and portion 10 to maintain the parts 7, 9 in spaced relation. The cross-piece 11 also provides a stop for a purpose to be presently referred to. The parts 7, 8, 9, and 10 provide a combined clamping and snuffer element of closed loop like form referred to generally at A.

75 The outer end of the arm 3 merges into a semi-circular part 12 which provides a combined coupling and snuffer element referred to generally at B and which is oppositely disposed with respect to the element A.

80 The part 12 extends between the parts 7, 9 and has its movement in a direction away from the parts 7, 9 arrested by the stop provided by the cross-piece 11. The slot formed by the parts 7, 8, 9 and 10 provides a clear-

ance for the outer end of the arm 3 and the part 12 when the latter is shifted in a direction towards the parts 7, 9. The portion 10 of the part 9 acts as a stop to arrest the shifting movement of arm 3 when part 12 is shifted in a direction towards parts 7, 9.

The combined clamping and snuffing elements A, B coact to detachably secure a cigarette 13 to the device. See Figures 1 and 2. 10 When the device is detachably connected to the cigarette 13 the latter can be conveniently positioned to be smoked between the lips of the smoker and removed therefrom when occasion requires. The elements A, B are resiliently supported by the arms 2, 3 respectively and these latter in connection with the handle part 1 normally tend to shift elements A and B towards each other thereby clamping the cigarette to the device. As the elements A, B normally tend to shift towards each other when in position for clamping the cigarette to the device, the arrangement provides that when the cigarette has been consumed to the point of connection between 20 the device and the cigarette, the elements A and B will be released and automatically function to snuff off the lighted end of the cigarette. When the elements A and B are released they shift towards each other to assume the position shown in Figures 3 and 4, but the movement relatively to each other will be arrested by the stop 11. When it is desired to attach a cigarette to the device, assuming that the device is in the position shown in Figure 3, the arms 2, 3 are moved towards each other to enable the positioning of the cigarette between the members A, B, after the cigarette has been positioned the arms 2, 3 are released whereby the elements 30 A, B set up a clamping action on the cigarette to detachably connect it to the device.

What I claim is:

1. A device for the purpose set forth comprising a pair of resilient arms, a semi-circular shiftable combined clamping and snuffer element integral with and offset with respect to the outer end of each arm, said elements being interengaged and oppositely disposed relatively to each other, one of said elements 45 having a slot for the passage therethrough of the other of said elements, the said element formed with the slot provided with means for arresting the shifting movement in opposite directions of said elements relatively to each other.

2. A device for the purpose set forth comprising a pair of opposed resilient arms, a semi-circular shiftable combined clamping and snuffer element integral with and offset 50 with respect to the outer end of each arm, said elements being interengaged and oppositely disposed relatively to each other, one of said elements having a slot for the passage therethrough of the other of said elements, the said element formed with the slot provided

with a stop for arresting the movement in one direction of said elements relatively to each other, and that element provided with the stop having means for arresting the shifting movement of said elements relatively to each other in the opposite direction. 70

3. A device for the purpose set forth comprising a pair of opposed resilient arms, a semi-circular shiftable combined clamping and snuffer element integral with and offset 75 with respect to the outer end of each arm, said elements being interengaged and oppositely disposed relatively to each other, one of said elements having a slot for the passage therethrough of the other of said elements, the said element formed with the slot provided with a stop for arresting the movement in one direction of said elements relatively to each other, and a split resilient loop having its ends integral with the other ends of said arms. 80

4. A device for the purpose set forth comprising a pair of opposed resilient arms, a semi-circular, shiftable combined clamping and snuffer element integral with and offset 90 with respect to the outer end of each arm, said elements being interengaged and oppositely disposed relatively to each other, one of said elements having a slot for the passage therethrough of the other of said elements, the said element formed with the slot provided with a stop for arresting the movement in one direction of said elements relatively to each other, that element provided with the stop having means for arresting the shifting movement of said elements relatively to each other in the opposite direction, and a split resilient loop having its ends integral with the other ends of said arms. 95

5. A device for the purpose set forth comprising a pair of opposed resilient arms, a semi-circular, shiftable combined clamping and snuffer element integral with and offset 100 with respect to the outer end of each arm, said elements being interengaged and oppositely disposed relatively to each other, one of said elements having a slot for the passage therethrough of the other of said elements, the said element formed with the slot provided with a stop for arresting the movement in one direction of the said elements relatively to each other, a split resilient loop having its ends integral with the other ends of said arms, and one of said arms provided with a horizontally disposed coil intermediate the ends 105 thereof. 110

In testimony whereof, I affix my signature hereto.

KALLE RINNE.
